S. Klahr,

Boring Wood.

N° 16,241.

Patented Dec. 16, 1856.

UNITED STATES PATENT OFFICE.

SAMUEL KLAHR, OF REAMSTOWN, PENNSYLVANIA.

BORING-MACHINE.

Specification of Letters Patent No. 16,241, dated December 16, 1856.

To all whom it may concern:

Be it known that I, SAMUEL KLAHR, of Reamstown, county of Lancaster and State of Pennsylvania, have invented an Improved 5 Boring-Machine; and I do hereby declare that the following is a full and exact description thereof, reference being had to the accompanying drawings, and to the letters of reference marked thereon, making a part 10 of this specification.

The nature of my invention consists in the combination of the several devices for boring posts and pump stocks which I call the improved "portable boring machine."

15 To enable others skilled in the art to make and use my invention I will proceed to describe its construction and operation.

A is a square frame supporting the devices for boring posts.

20 B is an extension frame, attached to frame A which supports the devices for boring pump stocks, or any long pieces of timber, lengthwise.

C is a railway carriage resting on the top 25 of frame A and carries the auger D.

E is a pulley on the shaft of auger D.

F is a lever attached to carriage C by which the carriage and auger D are moved forward while boring, or at any time withdrawn from the lumber or piece bored.

30 G a horizontal and adjustable platform to which the post or piece of lumber is attached, and which is moved crosswise, the required distance to regulate the holes apart. The 35 platform G has teeth underneath which are operated on by a pinion H, which pinion H is moved by the crank I.

J is a drum on the shaft K secured to the 40 frame A by journal boxes. The drum J causes the auger D to revolve by a band L passing around it and the pulley E.

On the shaft K is a pulley M which is put in motion by a band O passing around it and the main driving wheel P. The car-

riage Q (on the frame B) which carries the 45 pump stock to the auger D is attached to an endless chain R which passes around pulleys S and T. These pulleys are of three sizes, and the endless chain is placed over the larger or smaller pulleys according to 50 the speed required. The pulleys T have projecting pins U which catch hold of the links or apertures of the chain R, prevent its slipping, and assist in regulating its motion. The pulleys T have a pinion V on their shaft 55 which receives its motion from a vertical endless screw W on the upper end of vertical shaft X. This vertical shaft X has a pinion Y at its lower end. An endless screw Z on the horizontal shaft K gears into the 60 pinion Y on the vertical X, and the endless screw W gears into the pinion V and thus the pulleys T receive their motion.

What I claim as my invention and desire 65 to secure by Letters Patent is—

1. The arrangement and combination of the shaft X endless screw Z, pinion and pulleys T as operating on an endless chain and railway carriage for the purpose of boring 70 pump stocks as described.

2. I also claim the shape and construction of the pinion V and pulleys T with pins U, solid on one shaft, for the purpose herein set forth.

3. I do not claim the combination and arrangement of the drum J with the devices for operating the carriage C, but what I do claim as my invention is the combination and arrangement of the drum J with the devices for operating both of the carriages 80 C and Q for boring posts and pump stocks forming a neat portable boring machine substantially as herein set forth.

SAMUEL KLAHR.
